UNITED STATES PATENT OFFICE.

CHARLES E. KELLEY, OF CLARKSBURG, WEST VIRGINIA, ASSIGNOR TO UNDERWOOD TYPE-WRITER COMPANY, OF NEW YORK, N. Y., A CORPORATION OF NEW JERSEY.

TYPE-WRITING MACHINE.

No. 890,361.

Specification of Letters Patent.

Patented June 9, 1908.

Application filed July 12, 1907. Serial No. 383,426.

To all whom it may concern:

Be it known that I, CHARLES E. KELLEY, a citizen of the United States, residing in Clarksburg, in the county of Harrison and State of West Virginia, have invented certain new and useful Improvements in Type-Writing Machines, of which the following is a specification.

This invention relates to devices which 10 guide or support the paper, especially as it is being introduced around the platen of a type-writing machine.

Heretofore, gages and supports for the 15 side edges of the paper while it is being introduced into the machine, have been mounted directly upon the usual paper shelves which incline upwardly from the rear side of the platen; but these have been found more or 20 less objectionable on account of the difficulty of adjusting the same along the paper shelf and liability to scratch or mar the shelf.

According to my present improvements a suitable rail is mounted on the back side of the paper shelf, and the side gage for the 25 sheets is provided with supporting means extending back over the top edge of the paper shelf and engaging said rail. The finger-piece conveniently extending over the top of the paper shelf enables the operator to release the paper-gage or guide for ready adjustment along the rail and platen.

In the accompanying drawings, Figure 1 is a front elevation partly in section of the improved paper guide. Figs. 2 and 3, the latter 35 in section, are perspective views of the paper-gage and its carrier. Fig. 4 is a perspective view of a brake-lever or device to grip the rail along which the paper guide is adjusted. Fig. 5 is a perspective view of the improvements applied to the paper shelf of an Underwood typewriting machine, said paper shelf shown in dotted lines. Fig. 6 is an end elevation, partly in section, of a part of the 40 platen frame of an Underwood typewriting machine with my improvements applied thereto.

Type-bars 1 strike against the front side of a platen 2 mounted upon a platen frame comprising ends 3, and an intervening paper shelf 4; rollers 5, 6, running upon the under side of the platen to guide the paper 7 around the same. Mounted back of the platen (i. e. at the introductory side thereof) is a gage 8 for the side edge of the paper, said gage preferably in the form of a flange bent

up from a plate or finger 9 which serves as a support for the side edge portion of the paper. Usually two of the devices 8, 9 are employed, but I describe herein only one thereof with its supporting and adjusting means. 60 At its rear end, the plate 9 curves at 10 around the roll or bead 11, which usually constitutes the top edge of the paper shelf 4 in said machine. In rear of the paper shelf, the hook shaped part 10 is formed with an 65 ear 12 which is secured by a rivet 13 to the side 14 of a bracket-like carrier which slides upon rods 15, 16 parallel with the platen and supported by means of brackets 17 and screws 18 on the rear side of the paper-shelf; 70 said rod constituting a double track or rail along which the carrier slides together with the paper guide. Each of the slides 14, 19 of the carrier (designated as 20) is provided with openings 21, 22, to fit upon the rods 15, 75 16. The guide may hence be adjusted to any desired position along the platen 2, and liability of marring the paper shelf is avoided.

Upon the rivet 13 is pivoted a lever 23 that is pressed by a spring 24 up against the 80 under side of one or both of the rods 15, 16. The spring 24 is riveted at 25 to the carrier 20 and causes the end of the lever to operate as a brake to grip the rod, so that danger of accidental displacement of the guide 8 along 85 the rod or rail is avoided. An arm 26 of said lever curves forwardly above the top lever of the paper shelf 4, and is provided on its forward end with a key 27. By depressing the key, the lower part or shoe of the lever is 90 thrown down from the rail, as at Fig. 6, thus releasing the gage 8, so that it may be adjusted freely along the platen. Upon relieving the key 27 of pressure, the lever 23 again takes hold of the rail to secure the gage 95 8 in the position to which it is adjusted.

Variations may be resorted to in adapting the invention to different machines; and the same is also adapted for other uses.

Having thus described my invention, I 100 claim:

1. In a typewriting machine provided with a platen, a platen frame and a paper shelf in rear of the platen, the combination of a rail in rear of said paper shelf and extending therealong, a carrier mounted on said rail, an arm extending from said carrier forwardly over the top edge of the shelf, a gage upon said arm to guide the side edge of the paper, means upon said carrier to grip said 110

rail, and a finger piece to release said gripping means.

2. In a typewriting machine provided with a platen, a platen frame, and a paper shelf in rear of the platen, the combination of a rail mounted upon the rear of the paper shelf and extending therealong, and a guide forward of the paper shelf for the side edge of the paper, said guide having means extending back over

10 the top edge of the paper shelf and engaging said rail to support the guide and enable the latter to be adjusted along the platen.

3. In a typewriting machine provided with a platen, a platen frame, and a paper shelf in 15 rear of the platen, the combination of a rail mounted upon the rear of the paper shelf and extending therealong, a guide forward of the paper shelf for the side edge of the paper, said guide having means extending back over

20 the top edge of the paper shelf and engaging said rail to support the guide and enable the latter to be adjusted along the platen, a finger piece mounted over the top edge of the paper shelf, and rail-gripping means releasable by said finger piece.

4. In a typewriting machine provided with a platen, a platen frame and a paper shelf in rear of the platen, the combination of a rail mounted upon the rear of the paper shelf and 30 extending therealong, a paper-guide for-

ward of the paper shelf, said guide having means extending back over the top edge of the paper shelf and engaging said rail to support the guide and enable the latter to be adjusted along the platen, a brake, a spring 35 pressing said brake against a fixed part to prevent accidental displacement of the guide along said rail, and a key to release said brake.

5. In a typewriting machine provided with 40 a platen, a platen frame and a paper shelf in the rear of the platen, the combination of a rail mounted upon the rear of the paper shelf and extending therealong, a paper guide forward of the paper shelf for the side edge of the 45 paper, said guide having means extending back over the top edge of the paper shelf to engage said rail to support the guide and enable the latter to be adjusted along the platen, a lever pivoted upon said guide and 50 extending over the top edge of the paper shelf, a spring pressing said lever against a fixed part to prevent accidental displacement of the guide along said rail, and a key upon said lever to swing the same away 55 from said fixed device to release said guide.

CHARLES E. KELLEY.
